UNITED STATES PATENT OFFICE.

GEORGE T. STRITE AND FRANK H. BIERMAN, OF MINNEAPOLIS, MINNESOTA, ASSIGNORS OF ONE-FIFTH TO HOWARD J. BIERMAN AND ONE-FIFTH TO ENSLEY L. STRITE, BOTH OF MINNEAPOLIS, MINNESOTA, AND ONE-FIFTH TO J. S. CLAPPER, OF BILLINGS, MONTANA.

DRIVE-GEARING FOR TRACTION-ENGINES.

1,194,569.

Specification of Letters Patent. Patented Aug. 15, 1916.

Application filed January 16, 1914, Serial No. 812,471. Renewed May 6, 1916. Serial No. 95,920.

To all whom it may concern:

Be it known that we, GEORGE T. STRITE and FRANK H. BIERMAN, citizens of the United States, residing at Minneapolis, in 5 the county of Hennepin and State of Minnesota, have invented certain new and useful Improvements in Drive-Gearing for Traction-Engines, of which the following is a specification.

10 Our invention relates to drive gearing for traction engines of the type disclosed in our co-pending application Serial Number 812,470, filed January 16, 1914, and the means for supporting, assembling and housing said drive gearing upon the frame of the traction engine.

15 It is the object of our present invention to provide a system of drive gearing which shall be particularly simple, efficient and 20 compact and which shall be related to the frame of the engine so as to be capable of being housed for protection from dust and for lubrication in such a way that the frame forms a part of said housing and the removable cap is easy to be got at and does not engage with any bearing or moving part, although affording in combination with the frame and bearing castings a complete and efficient dust proof casing.

25 30 The full objects and advantages of our invention will appear in connection with the detailed description thereof and are particularly pointed out in the claims.

35 In the drawings, illustrating the application of our invention in one form,—Figure 1 is a plan view partly in section of a traction engine embodying our improvements. Fig. 2 is an elevation of the same portion viewed from the side at the top of Fig. 1.

40 45 50 As shown in the drawings, and corresponding to the disclosure of the aforesaid application, a substantially rectangular frame 10 of channel iron is provided, and a longitudinal beam 11 extends along said frame spaced a short distance from a side member thereof. A single traction wheel 12 is carried by a live axle or integral hub 13 which is journaled in removable roller bearings 14, as indicated in dotted lines in Fig. 2. These bearings are set into a bearing block 14' at one side of the machine and into a portion 30 of a casting 31 at the other side of the machine. The casting 31 is

formed as an extended U-piece having an end 32 and a side 33 similar to side 31, the 55 sides 31 and 33 being bolted along the channels 10 and 11 and end 32 bridging the space between said channels. It thus appears that the frame 10 is in effect suspended upon the axle or hub 13. A drawbar 15 60 is suspended by yoke arms 16 from the frame 10 and is connected by draft links 17 directly with extended portions of the bearing blocks 14' and 30. Fast on the hub 13 and positioned between the casting portions 65 31 and 33 and the frame members 10 and 11 is a spur driving gear 18 by which the traction wheel 12 is driven. The spur gear 18 meshes with a pinion 19 on the short shaft 20 operating in bearings 21 and 22 set 70 into the casting walls 31 and 33, respectively. Extending from the end wall 32 of the casting is a portion 23 which provides a bearing for a longitudinal drive shaft 24 which is operated by a motor and 75 transmission, not shown, upon the forward part of the frame. The shaft 24 has thereon a bevel pinion 25 which meshes with a bevel gear 26 fast with the pinion 19. The bevel gear 26 extends between casting walls 80 31 and 33 and frame members 10 and 11 alongside of spur gear 18, and the drive shaft 24 is in the same plane as the spur gear 18. It will be apparent that this gearing is included in a very narrow space and 85 that a perfectly balanced support upon both longitudinal frame members 10 and 11 is provided. The drive gearing thus compactly positioned is provided with an exceedingly simple casing which is dust-proof 90 and oil-retaining and embodies the casting walls 31, 32 and 33 and the frame beams 10 and 11. The lower casing section 27 is bolted or riveted to the lower flanges of the channel beams 10 and 11. Filler strips 28 95 and 29 are bolted in position between the channel irons at the ends of the gear space, as best indicated in Fig. 2, the filler strip 29 coöperating with the end wall 32 of the casting to complete the lower part of the 100 casing. A removable cap 34 is provided with a flanged base 35 which flanges rest upon flanged extensions 36 of the casting 31 throughout the extent thereof and upon the top of the channel beam flanges 10 and 11, the removable section 34 being bolted 105

into position by means of these flanges, as indicated. A casing 37 may, if desired, be used to inclose the upper part of traction wheel 12. It will be seen that by this means an oil-receiving and dust-proof casing for the driving gear is provided with a readily removable section which does not engage any of the moving or bearing portions of said gearing. The gears 18 and 26 will run in oil within this casing and, all dust and dirt being excluded, will operate easily and with the least possible loss of power from friction. When it is considered that our engine is to be operated in plowing and cultivating where exposure to sand and dirt is necessarily very great, the advantage of our dust-proof and oil-containing casing will be apparent. Furthermore, by the use of overlapping gears 18 and 26 both of said gears may be made of comparatively small diameter and compactly positioned for housing and at the same time the leverage of a single very large gear be obtained. The shortness of the shaft 20 with its double bearing and the drive shaft 24 operating in the plane of gear 18 transmits the power from said longitudinal drive shaft without any torsional strain and has the effect of a straight spur gear drive notwithstanding the employment of the bevel gear 26 overlapping spur gear 18.

We claim:

1. A traction engine comprising a single traction wheel, a frame supported by said traction wheel embodying a longitudinal member on one side of the wheel and two parallel spaced longitudinal members on the other side of the wheel, and drive gearing for the traction wheel located between and supported by the two parallel spaced members alongside of the traction wheel.

2. A traction engine comprising a single traction wheel, a frame supported by said traction wheel embodying a longitudinal member on one side of the wheel and two parallel spaced longitudinal members on the other side of the wheel, drive gearing for the traction wheel located between and supported by the two parallel spaced members alongside of the traction wheel, and a housing for said drive gearing directly supported by both said parallel spaced members.

3. A traction engine comprising a frame having three longitudinal members extending in parallel relation and unequally spaced, a single traction wheel extending between the more widely spaced members and supporting the frame, a spur gear secured to move with the traction wheel and drive the same, and driving mechanism for said spur gear including a driving gear supported by and extending between the more closely spaced members in overlapping relation to the spur gear.

4. A traction engine comprising a frame

having three longitudinal members extending in parallel relation and unequally spaced, a single traction wheel extending between the more widely spaced members and supporting the frame, a spur gear secured to move with the traction wheel and drive the same, driving mechanism for said spur gear including a driving gear supported by and extending between the more closely spaced members in overlapping relation to the spur gear, and a housing for said driving mechanism supported by both said more closely spaced members.

5. A traction engine comprising a single traction wheel, a frame supported by said traction wheel embodying a longitudinal member on one side of the wheel and two parallel spaced longitudinal members on the other side of the wheel, a driving gear secured to move with the traction wheel and drive the same, and drive gearing for operating the driving gear extending between and supported by said two parallel spaced members.

6. A traction engine comprising a single traction wheel, a frame supported by said traction wheel embodying a longitudinal member on one side of the wheel and two parallel spaced longitudinal members on the other side of the wheel, a driving gear secured to move with the traction wheel and drive the same, drive gearing for operating the driving gear extending between and supported by said two parallel spaced members, and a housing for said drive gearing supported by both said more closely spaced members.

7. A traction engine comprising a single traction wheel, a frame supported by said traction wheel embodying a longitudinal member on one side of the wheel and two parallel spaced longitudinal members on the other side of the wheel, a driving gear secured to move with the traction wheel and drive the same, a short shaft journaled upon said parallel members, a pinion on said shaft meshing with the driving gear, a gear on said short shaft extending between said members and overlapping the driving gear, and means for driving the second-named gear.

8. In combination with the traction wheel and frame of a traction engine having a pair of spaced longitudinal members at one side of the traction wheel, a live axle extending across said spaced members by which the traction wheel is driven, a spur gear fast on said axle between said members, a short shaft supported at its ends by said members, a pinion on said shaft meshing with the spur gear, a bevel gear on said shaft extending between the members and overlapping the spur gear, and a longitudinal shaft having a bevel pinion meshing with said bevel gear.

9. In combination with the traction wheel

- and frame of a traction engine having a pair of spaced longitudinal members at one side of the traction wheel, a live axle extending across said spaced members by which the 5 traction wheel is driven, a spur gear fast on said axle between said members, a short shaft supported at its ends by said members, a pinion on said shaft meshing with the spur gear, a bevel gear on said shaft extending 10 between the members and overlapping the spur gear, and a longitudinal shaft having a bevel pinion meshing with said bevel gear, said longitudinal shaft extending in the plane of the spur gear.
- 15 10. In combination with the traction wheel and frame of a traction engine having a pair of spaced longitudinal members at one side of the traction wheel, an integral casting secured upon the top of said members and having spaced side walls with the interiors thereof coincident with the interior walls of said members, a live axle journaled in said casting and extending across said members, a spur gear on said axle extending 20 between said members and the walls of said casting, a short shaft journaled at its ends in said casting, a pinion on said shaft meshing with the spur gear, a bevel gear on said shaft extending between the frame members 25 and the side walls of the casting, and a longitudinal shaft journaled in the end of said casting and having a bevel pinion thereon meshing with said bevel gear.
11. In combination with the traction 30 wheel and frame of a traction engine having a pair of spaced longitudinal members at one side of the traction wheel, an integral casting secured upon the top of said members and having spaced side walls with the 35 interiors thereof coincident with the interior walls of said members, an axle for said traction wheel and operative gearing journaled in said casting and extending between the frame members and the side walls of the 40 casting, and casing sections applied to the 45
- lower portions of said frame members and to the upper portions of the frame member and casting for providing a dust-proof casing for said gearing.
12. In combination with the traction 50 wheel and frame of a traction engine having a pair of spaced longitudinal members at one side of the traction wheel, an integral casting secured upon the top of said members and having spaced side walls with the 55 interiors thereof coincident with the interior walls of said members, an axle for said traction wheel and operative gearing journaled in said casting and extending between the frame member and the side walls of the casting, and casing sections applied to the lower 60 portions of said frame members and to the upper portions of the frame member and casting for providing a dust-proof casing for said gearing, at least one of said casing sections being removable.
13. A traction engine comprising a single traction wheel and a frame surrounding and supported by said wheel having a pair of spaced longitudinal members at one side of the traction wheel, a live axle by which the traction wheel is driven extending across and journaled upon said spaced members, a wide spur gear upon said axle operating in the space between said longitudinal members, a drive shaft journaled upon and extending in parallel relation with said longitudinal members in the plane of said spur gear, and gearing operatively connecting said drive shaft and spur gear, including a 70 large bevel gear operating between said longitudinal members in overlapping relation with the spur gear.
- In testimony whereof we affix our signatures in presence of two witnesses.
